UNITED STATES PATENT OFFICE.

JOSEPH R. FINNEY, OF PITTSBURG, PENNSYLVANIA.

ELECTRIC-LIGHTING APPARATUS.

SPECIFICATION forming part of Letters Patent No. 234,261, dated November 9, 1880.

Application filed November 7, 1879.

To all whom it may concern:

Be it known that I, JOSEPH R. FINNEY, of Pittsburgh, in the county of Allegheny and State of Pennsylvania, have invented a new and useful Improvement in Electric Lights; and I do hereby declare the following to be a full, clear, and exact description thereof.

My invention relates to the construction and arrangement of apparatus for electro-lighting, in which several electric lights or series of lights are arranged in the same electric circuit, and each light or series of lights is operated by a leak or deflected current passing by a branch wire from the main line to the ground; and it consists, first, in the application thereto of a galvanometer to indicate the amount of electric current passing over the main line, and combining therewith an adjustable regulator so arranged as to be operated by the galvanometer, and thereby to adjust the amount of current on the main line to the greater or less number of lights in operation from time to time; second, in combining with each such light or group of lights in a circuit such as just described, a resistance device to limit the amount of leak from the main line, a regulator for adjusting the amount of electricity supplied to each light or group of lights, or to shut off the supply at will, and a ground connection; and, third, in the construction of an automatic device for feeding the movable carbon point of an electric light toward the stationary carbon point, so as to secure uniformity of light.

In the accompanying drawings, Figure 1 is a diagram representing the arrangement of several lights in an electric circuit and the devices employed for governing and regulating the quantity and force of the electric current supplied thereto. Fig. 2 is a plan view of the arrangement of devices for regulating the supply of electric current to the lights. Fig. 3 is a vertical section through *xx* of Fig. 2. Fig. 4 is a vertical elevation, partly in section, of an electric candle with automatic feed device.

In the several figures like letters refer to the same parts.

My improvement in the arrangement of several electric lights in one circuit is applicable

to most, if not all, of the known forms and constructions of electric candles, and is not peculiar to that shown in the drawings accompanying this specification.

In Fig. 1, *a* is the main line of wire, starting from the battery *B* at one terminal station, *A*, and extending continuously to the other terminal station. This wire is designed to supply the electric current from a galvanic battery, or from a magneto-electric machine, to several electric candles located at different points, or to several groups of electric candles, as the case may be. By "a group of electric candles" I mean several candles placed in one building or room, each individual candle or group of candles having a separate ground-connection.

In my improved method of supplying the electric current to a number of electric lights in the same circuit the electric connection of the main wire between the several lights or groups of lights is unbroken and continuous throughout the circuit, each light or group of lights being supplied by a leak or side current from the main wire, which runs to the ground, while the main current passes on, the main wire supplying each light or group of lights with its requisite quantity of the electric current, the amount of which is regulated at each light or group of lights by an adjustable resistance device, *R*.

From the main-wire *a* a branch wire, *b*, in electrical connection therewith, extends to each separate candle *c* or group of candles, and thence connects with the ground or with a ground-wire, *d*, by a wire, *e*.

In Fig. 1 candles are not represented, but are supposed to be located at the point *c*, being connected to the branch wire *b* and ground-wire *d*.

Having thus described the general arrangement, I will proceed to describe the devices I employ for regulating the force of the electric current passing over the main wire *a* to supply all the electric candles on its circuit.

At or near the point where the battery *B* is located there is interposed in the main wire *a* an adjustable resistance device consisting of a glass tube, *f*, containing pulverized carbon. Each end of this glass tube is set in a metallic

90

100

end piece, g g' , to each of which one end of the wire a is attached, so that the electric current must pass through the carbon contained in the glass tube f . A screw-shaft, h , works in a female screw in one of the metallic end pieces, g' , of the glass tube, and the extremity of the screw-shaft enters the glass tube f , and when screwed down presses upon the carbon contained therein.

10 The electric current does not pass unless the end of the screw-shaft touches the carbon, and the intensity of the current increases as the carbon is compressed by the screwing down of the shaft h . On the outer extremity 15 of the screw-shaft is a pulley, i , around which a band passes to a pulley, i' , on the indicator. The indicator is designed to indicate the force of the electric current employed, and also to operate automatically on the resistance device R .

15 The construction of the indicator is shown in Figs. 1, 2, and 3. k is a brass spool, which is made long and narrow, having a cavity sufficient in length to allow of the free play within it of a magnetic needle, n , which is rigidly attached to an upright shaft, m , which passes through the spool and has its bearings therein. On the upper side of the spool k is a dial-plate, p , through the center of which the shaft m projects. To the shaft m is rigidly attached the pulley i' , before referred to, and a hand, o , which points to graduation-marks at the circumference of the dial-plate p . The indicator is so placed that the magnetic needle n , when 30 in the magnetic meridian, is parallel to the sides of the spool and the hand o points to zero on the dial-plate. A piece of fine covered wire, l , is coiled around the spool k , one extremity of this wire being connected with 35 the main wire a beyond the carbon resistance device before described, and the other end is connected with the ground or the ground-wire d . On the wire l , between the indicator and the main wire a , is interposed a resistance-coil, r .

40 The operation of this apparatus is as follows: When the end of the screw-shaft h is brought in contact with the carbon in the adjustable resistance device the electric current passes through the main wire a , the circuit being complete. A portion of the current passing through the carbon resistance device passes off through the wire l and around the spool k of the indicator to the ground at G , and in so doing deflects the magnetic needle n more or less, according to the amount and force of the current so drawn from the main wire. Of course it is only a small portion of the current from the battery B which thus passes 45 through the indicator; but the resistance offered by the resistance-coil r , added to the resistance of the wire wound around the spool k , being constant and not changeable, the amount of current passing through the indicator will 50 bear a definite proportion to the whole current passing from the battery through the ad-

justable resistance f , and thus the deflection of the hand o of the indicator will indicate the force of the current passing over the main wire a by means of the properly-regulated graduation of the dial-plate p . As, however, the hand o is connected with the shaft h of the carbon resistance device by means of a belt, as shown, or by gearing, if preferred, the deflection of the hand o will cause the turning 70 of the shaft h and the consequent decrease of compression of the carbon in the glass tube f , which will increase the resistance and check the force of the flow of the electric current from the battery B over the main wire a . 75 This in turn causes the deflection of the needle n and hand o to diminish, which acts upon the screw-shaft h to lessen the resistance to the flow of the current, and by this means a constantly-uniform flow of the electric current 80 over the main wire a is attained by placing in the main circuit an adjustable resistance device, which is mechanically adjusted by the deflection of the needle of a galvanometer operated by a side current or leak from the main 85 wire.

I will now proceed to describe the means I use for regulating the force of the electric current supplied to each electric light or group of lights, as shown in Fig. 1.

90 From the main wire a a branch wire, b' , extends to each electric light or group of lights to be supplied by the current from the main wire. The branch wire b' is connected with a resistance-coil, r' , and thence connects with an adjustable resistance device, R' , consisting of a glass tube, f' , containing carbon, and constructed as before described. The wire thence passes to and is connected with the electric candle or group of candles located at c , and thence connects with the ground or ground-wire at G' . It will thus be seen that the electric candle or group of candles at c is supplied with the electric current through the branch wire b' from the main wire a , and that the amount of current allowed to pass to the candle or candles is limited by the resistance-coil r' in the first instance, and still further by the adjustable resistance device R' , so that the electric current may be entirely cut off from 100 the electric candle or candles at c by screwing the shaft h' of the resistance device R' until it ceases to form contact with the carbon, and the connection may be at once restored by means of the screw-shaft h' . So, also, the amount of electric current passing to the candle or group of candles at c is regulated by turning the shaft h of the resistance device R' so as to increase or diminish the compression of the carbon in the glass tube, or the current may 105 be entirely cut off by breaking the contact between the shaft h' and the carbon in the glass tube f' . In Figs. 1 and 2 the place of the electric candle is indicated at c . The wire from the resistance device R' is connected, as herein-after described, with the holder of the upper carbon point, x , of the electric candle, while 110

the wire e' , which connects with the ground, is also connected with the post d , which supports the lower carbon point, x' .

I will now proceed to describe a peculiar arrangement of the electric candle by which an automatic feed of one of the carbon points, x , is effected, so as to preserve its proper relative position to the other carbon point, x' .

This construction is shown in Fig. 4, in which q is the standard of the candle, which may be made of glass or other good non-conductor, or if not is insulated from the base. Attached to the standard q by a sleeve, v , is a bracket-arm, w , (shown in dotted lines in Fig. 4,) which extends from the standard q , and is attached to and enters the side of the sleeve v , through which sleeve v passes an iron rod, z , fitting loosely therein.

The sleeve v and rod z are placed vertically in exact line with the socket y , in which the lower carbon point, x' , is inserted, the upper carbon point, x , being secured in the rod z . From the post a fine silk-covered wire, f' , extends up through the standard q , and is wound around a spool, S , on the bracket-arm w , so that the passage of the electric current through it makes an electro-magnet of the soft-iron bracket-arm w , which enters the sleeve v sufficiently to come in contact with the iron rod z . The wire f' , after passing around the arm w , is connected with the sleeve v , so as to complete the circuit through the rod z and carbon points x x' to the ground. The result of this construction is, that as the electric current passes from the main wire a through the wire f' the bracket-arm w becomes magnetized and attracts to it the rod z , holding it securely in place. As soon, however, as the carbon points consume away sufficiently to break the continuity of the electric current through the carbon points x x' the arm w becomes demagnetized and no longer attracts and retains the rod z in place. The rod z then slides down until the carbon points x x' approach sufficiently near to restore the broken current, when the arm w is remagnetized and again holds the rod z in its proper position. In practice, however, the current is never entirely broken, but the rod keeps its proper place by a gradual descent. The amount of wire wound around the spool S is so regulated as to magnetize the arm w sufficiently to effect this result.

It will be observed that in my method of operating a number of single electric candles or groups of candles on a single circuit, instead of passing the entire current from the battery through each candle, and thence through the next candle, and so on through all the electric candles in the series, I pass only a portion of the current through each individual candle or group of candles, and run that portion of the current directly to the ground, the remainder of the current passing on by the main wire to the next candle or group of candles, and so on

throughout the circuit; that the amount or portion of the current which is thus carried off as a side current to operate each individual electric candle or group of candles is limited and determined by a resistance device interposed between the main wire and the candle or candles, as shown in Figs. 1 and 2, or, if preferred, between the candle or group of candles and the ground, as in Fig. 3, as may be found most convenient; and, further, that the amount of electric current passing to each light or group of lights is further regulated at the will of the operator by an adjustable resistance device, also located on the branch wire between the main wire and the ground; and that by means of the use of a branch wire and side current to each individual light or group of lights the electric connection between any such light or group of lights may be severed without in any way interfering with the main current or interfering with the burning of any other electric lights placed in the same circuit but fed by a different branch wire. As the current grows weaker, owing to the successive leakage to supply the side currents, the amount of resistance interposed on the branch wires between the main wire and the candles is decreased, so as to give the required force of current and intensity of light to each successive candle or group of candles.

Where a group of electric lights are placed in a single building or room, which are all to be used together, they are supplied by a single branch wire, the current passing from one to the other before passing to the ground; but if preferred a separate resistance device may be applied to each separate candle.

Having thus described my improvements in apparatus for electric lights, what I claim as my invention, and desire to secure by Letters Patent, is—

1. In an electric circuit, the combination of a galvanometer operated by a leak from the main line, through a resistance with a regulator operated by the galvanometer, substantially as described.

2. The combination, with an electric light or group of lights arranged on a branch from a main electric circuit and operated by a leak therefrom, of a galvanometer and a regulator operated thereby, each such light or group of lights having an independent regulator and resistance device, substantially as described.

3. In an electric lamp, the combination of a carbon-holder of iron loosely inserted in a sleeve with the core of an electro-magnet entering the sleeve so as to come in contact with the carbon-holder, substantially as and for the purpose described.

In testimony whereof I, the said JOSEPH R. FINNEY, have hereunto set my hand.

JOSEPH R. FINNEY.
